Primary Examiner — Ian Simmons*Assistant Examiner* — Shannon Morgan*(74) Attorney, Agent, or Firm* — Muncy, Geissler, Olds & Lowe, P.C.(57) **CLAIM**

The ornamental design for a display screen with graphical user interface, as shown and described.

DESCRIPTION

The sole FIGURE is a front view of a display screen with graphical user interface showing my new design.

The broken lines shown in the sole figure represent portions of the display screen with graphical user interface that form no part of the claimed design.
